D3-15

AU 292

EX

OR D 1,702

No 1,702.

John A. Nobles
Design for a cane-Head, Umbrella Handle, Sword Hilt &c.

Patented Dec. 23. 1862

Fig. I

Fig. 2

Witnesses,
J. C. Wilson } John A. Nobles
E. Corans & } By city, A. A. Strongham.

UNITED STATES PATENT OFFICE.

JOHN C. NOBLES, OF RUSHFORD, NEW YORK

DESIGN FOR A CANE-HEAD, UMBRELLA-HANDLE, OR SWORD-HILT.

Specification forming part of Design No. 1,702, dated December 23, 1862.

To all whom it may concern:

Be it known that I, JOHN C. NOBLES, of Rushford, in the county of Allegany and State of New York, have invented or produced a new and original Design for a Cane-Head, Umbrella-Handle, Sword-Hilt, or other similar purpose; and I do hereby declare the following to be a full, clear, and exact description thereof, reference being had to the accompanying drawings, making a part of this specification, in which—

Figures 1 and 2 represent, in perspective, views from different sides of the head, handle, or hilt, so as to show the whole configuration and design.

A represents a part of a branch or trunk of a tree, upon which is perched an American eagle B, guarding her nest of eaglets C from a rattlesnake D, that is coiled around the branch or trunk and threatening the eaglets. The eagle has the snake grasped in its talons, and with its bill is drawing the folds of the American flag around its nest and young ones.

Upon the base or lower end of the branch, trunk, or handle there may be an escutcheon

E, for containing the name or initials of the owner, maker, or other person; but this may be omitted without impairing the general design, and is not regarded as a part of the design.

This design I propose to make and have made of both metal and ivory. The metal ones, made by electrotyping and afterward (if of the grosser metals) electroplated, are much the cheaper, but the ivory heads—carved, as of course they must be—are highly artistic. They may be molded from composition, such as factitious ivory or other compositions.

Having thus described my invention or production, what I claim as a new and original design for a cane-head, umbrella-handle, sword-hilt, and other similar purposes, is—

The configuration or ornamentation hereinabove set forth and explained.

JOHN C. NOBLES.

Witnesses:

A. B. STOUGHTON,
EDM. F. BROWN.